US00D809742S

(12) **United States Design Patent** (10) **Patent No.:** **US D809,742 S**
Staub (45) **Date of Patent:** **** Feb. 13, 2018**

(54) **GARMENT**

(71) Applicant: **NIKE, Inc.**, Beaverton, OR (US)
(72) Inventor: **Andrea J. Staub**, Portland, OR (US)
(73) Assignee: **NIKE, Inc.**, Beaverton, OR (US)

(**) Term: **15 Years**

(21) Appl. No.: **29/596,165**

(22) Filed: **Mar. 6, 2017**

(51) LOC (11) Cl. **02-02**

(52) U.S. Cl. **USPC D2/731**

(58) **Field of Classification Search**

(57) **CLAIM**

The ornamental design for a garment, as shown and described.

DESCRIPTION

FIG. 1 is a front perspective view of a garment showing my new design;

FIG. 2 is a front view thereof;

FIG. 3 is a side view thereof;

FIG. 4 is a second side view thereof; and,

FIG. 5 is a rear view thereof.

The long and short broken lines depict boundaries that form no part of the claim.

The even-length broken lines shown in FIGS. 1-5 are directed to environment, are for informational purposes only, and form no part of the claimed design.

1 Claim, 5 Drawing Sheets
